EDWARD FARON, OF NEW YORK, N. Y.

Letters Patent No. 83,769, dated November 3, 1868.

IMPROVED BRICK-MACHINE.

The Schedule referred to in these Letters Patent and making part of the same.

To all whom it may concern:

Be it known that I, EDWARD FARON, of the city of New York, in the county and State of New York, have invented certain new and useful Improvements in Machines for Moulding and Pressing Bricks; and I do hereby declare that the following is a full, clear, and exact description thereof, reference being had to the annexed drawings, forming part of this specification, in which—

Figure 1 is a front elevation of a brick-machine embodying my improvements.

Figure 2 is a side elevation thereof, showing the hopper, a portion of the mould-carriage, and one plunger, in section.

Figure 3 is a plan or top view of the machine.

Figure 4 is a vertical section taken transversely through the head-block, two moulds and two plungers, on the plane of the line $x x$, fig. 3.

Figure 5 is a vertical section, taken longitudinally through the head-block, one mould and its plunger, on the plane of the line $y y$, fig. 3.

Figure 6 is a plan or top view of two moulds, showing the plates which form the sides of the moulds.

Figure 7 is a plan view of the mechanism by which the pressed brick is removed from the face of the mould-carriage.

Figure 8 is a vertical transverse section, taken on the plane of the line $z z$, fig. 7, showing a sponge or other absorbent of oil in the pusher-block, for lubricating the moulds.

Similar letters of reference indicate like parts in all the figures.

The nature of my invention consists in a system of toggle-bars or levers, for operating the plungers to press the bricks, and to revolve the mould-carriage, whereby great power and precision in operation are obtained; also in providing the head-block, against which the clay is pressed, with perforations for permitting the escape of air or bubbles of water from the clay whilst the same is being pressed and moulded, and with a movable plate, which is directly over the moulds, and which can be removed for planing when necessary; also in a pushing-block and its actuating-mechanism, as hereinafter described, in combination with the mould-carriage for moving the bricks from off the mould-carriage, after the same have been delivered up to the face of the mould-carriage; also in an arm, in combination with the plungers, for supporting the latter until their lower ends rest upon the inclined plane.

A designates the foundation or bed of the machine. B is a driving-wheel mounted on a shaft, a , and deriving motion from any suitable motor, by means of a belt, a' , or any other suitable mechanism. C is a bevel-gear wheel mounted on the shaft a , with which wheel C there engages another bevel-gear wheel, D, the latter being mounted on a vertical shaft, D, which has its bearings, at its lower end, in a box formed in or attached to the foundation of the machine, and at its

upper end in a transverse beam, b, secured to vertical supports, b' b', rising from the top of the machine, or, more definitely speaking, from the top of the hopper E, (as shown in figs. 1 and 2,) to which latter they are bolted at their lower ends. On the top of this vertical shaft D a gear-wheel, F, is secured, which engages with another gear-wheel, F', mounted on the top of the shaft G of the mixing and forcing-screw or propeller. This mixing-screw or propeller consists in detail (refer to fig. 2) of the shaft G, to which is secured a number of arms, c c', those, c, serving as mixers, and those, c', as propellers, to press the clay downward, and these latter are constructed and arranged much like the wings of a propeller-wheel, and operate in much the same manner.

The hopper E is conical in shape, its greatest diameter being at the top, and the mixing and forcing-propeller G c c' is fitted to revolve therein, and to conform to the taper thereof. It is well-known that clay should be properly mixed, even after being ground, before being moulded or pressed into bricks, and these arms c accomplish the mixing thoroughly, and after this the clay drops down to the propeller-wheels c', to be forced by them down into the moulds d d, in the horizontally-revolving mould-carriage H, as will be understood by reference to fig. 3. This mould-carriage H is mounted on a central post, I, and is arranged to revolve in a horizontal direction, and in such manner as to bring the moulds d d directly under the discharging-end of the hopper E.

J J are the plungers, (see figs. 2, 4, and 5,) which are of a size to fit into the moulds d d, and they are prevented from dropping down too far by a ring or stop-piece, t, attached to the lower face of the mould-carriage, or formed therewith, as most convenient and desirable, a shoulder formed upon the lower part of said plungers resting on such ring t, as shown in figs. 2 and 5. Any other suitable arrangement may, of course, be employed for preventing the plungers dropping out of the moulds whilst passing from the hopper to the pusher-block, presently to be described.

K (refer to fig. 1) is a pusher-block for forcing the plungers up in the moulds, at the proper time to press the clay in the moulds into the proper size for bricks. The pusher-block (refer to fig. 1) is attached to one of a pair of toggle-bars, e e', the lower bar, e, being journaled in a box, z, secured to the foundation of the machine. At the point where the bars e e' are jointed together, there are connected two pitman-rods, f f', arranged parallel with each other, which rods, by means of a pin passing through an arm or pitman, j, connected to a crank, j', upon the shaft a, are jointed to two other rods, f f', which latter have their outer ends pivoted in the foundation of the machine. These rods f f' operate as toggle-bars. At the point where the toggle-bars f f' are connected together there is also pivoted a rod, g', which is attached to a vertical lever, g, and the said vertical lever is pivoted in the founda-

tion of the machine, so as to have a to-and-fro motion, and at the top of said vertical lever a drawing-pawl, *h*, is connected by a ball-joint, or in any other suitable way. The outer end of said draw-pawl, *h*, carries a hook, which catches against teeth, *i*, (see figs. 1 and 3,) formed upon the periphery of the mould-carriage *H*, and causes the same to revolve a certain distance at stated intervals of time. This arrangement of toggle-bars is an important feature of my improvements. It will be understood that, though I have described two bars, *f f*, and two bars, *f' f'*, only one of each can be used, instead of the two, if desirable.

The box *z*, in which the lower end of the toggle-bar *e* is pivoted, is bolted or secured to the foundation of the machine, in such manner that it can be raised by wedges or blocks placed under it, and thus the two toggle-bars *e e'* can be raised. This provision for a vertical adjustment of the toggle-bars *e e'* enables the bricks to be made larger or smaller, as is evident, inasmuch as the upper bar, *e*, throws the plungers farther or not so far up into the moulds, and hence the size of the bricks can be regulated.

L is an inclined plane extending part way round the central post, *I*, ascending from the pusher-block *K* nearly to the hopper, and then descending, upon which plane the ends of the plungers ride, in order to discharge the bricks from the moulds, as will be herein-after explained.

L', fig. 1, is an arm secured to a lug, *d*, projecting from the inclined plane, and arranged in such manner as to be pressed by a spring, *a'*, against the lower part of a plunger, as it comes round to it; and when each successive plunger is pushed up by the pusher-block *K*, the said arm will be forced, by means of said spring, under a shoulder on said plunger; and after the pusher-block *K* is drawn down, said plunger will rest on said arm, and be supported whilst being carried round, until its lower end rests on the inclined plane *L*, and hence the plungers, after they have been forced up to press the clay, are not allowed to drop, only a very little, and thus the pressed clay is permitted to expand a very little before it is forced out of the moulds, and the pressed bricks come out in a perfect state.

N is a beam or head-block, secured at its inner end to the hub *I*, and at its outer end to a vertical post, *M*. The said head-block is arranged so as to press upon or very closely to the face of the mould-carriage *H*. The moulds, after having been filled with clay while under the hopper *E*, are brought round under this head-block, and up against it the clay is pressed by the plungers, in order to form the bricks. At the point where this head-block rests over the mould-carriage, it is planed truly and evenly, so as to fit snugly.

It has been found that by permitting the air and bubbles of water to escape from the clay during the pressing and moulding-operation, much more perfect bricks can be produced. I accomplish this object by making slots, *q*, transversely through the head-block *N*, (refer to figs. 1, 4, and 5,) where the same rests over the moulds, and by making perforations, *r*, through the wall or face of the head-block *N*, directly over the moulds. These perforations are very small, but larger at the top than at the bottom, as shown clearly in figs. 4 and 5, and through these escape the air and bubbles of water which may be in the clay whilst the same is being pressed and moulded. I have shown, in figs. 1, 4, and 5, a plate, *P*, set into the head-block *N*, under the slots and over the moulds, against which the clay is pressed; and this plate *P* can be taken out, for planing the same, whenever necessary. The clay which may ooze through these perforations *r* can be pushed out of the slots *q* with a rod or stick.

The moulds *d d* are lined with plates, *s*, (refer to figs. 4, 5, and 6,) which are properly fitted therein in any proper manner, as will be seen by reference to fig. 6. These plates can be removed, for smoothing or planing the same, should it be necessary, and they can be ad-

justed so as to increase or diminish the size of the mould. Corresponding-sized plungers are, of course, in such cases, to be used.

The means employed for removing the bricks from the face of the mould-carriage, after the same have been pushed out of the moulds, by the plungers sliding up the inclined plane to a point which brings their faces flush with the top of the mould-carriage, consists of a block, *O*, (refer particularly to figs. 1 and 7,) which is connected, by means of an arm, *u*, to a lever, *V*, the said lever *V* being pivoted to a block, *w*. The outer end of this lever carries a pin, *x*, which travels in a groove in a cam, *R*, secured to the vertical shaft *D*. The said block *O* is steadied and guided by two rods, *r r*, and it is caused to move back and forth by the lever *V*, which is actuated by the pin travelling in the cam or groove, and it pushes the bricks off the face of the mould-carriage into or upon any suitable receiver, as the same are delivered from the moulds. This block *O* is provided with a cavity, (see dotted outlines in fig. 7,) into which is placed a sponge or other absorbent of oil, so that when the said block is brought over the moulds, the latter and the face of the plungers will be lubricated, whereby the adhesion of the clay to the plungers and the sides of the moulds is, in a great measure, prevented.

The operation of the machine is as follows:

The ground clay is fed into the hopper *E* in any suitable manner. I have shown, in fig. 1, an endless belt, *z*, carrying cups, which take up the clay and deposit it in a trough leading to the hopper. This clay is thoroughly mixed in the hopper by the arm *c*, and forced down into the moulds by the propeller-wings *c'*. The mould-carriage is then revolved by the draw-pawl *h*, sufficiently to bring another mould or pair of moulds under the hopper, and so on, till the moulds first filled are brought so that the plungers *J* are directly over the pusher-head *K*, which, by means of the toggle-mechanism, throws up said pusher-head, and presses the moulds the clay. As the pusher-head descends, a shoulder on the plungers rests on the arm *L'*, until carried round far enough for their lower ends to rest upon the inclined plane *L*. The same operation continues till the moulds containing the pressed and moulded bricks are brought in front of the pusher-block *O*, where, as before stated, the plungers will have pushed the bricks up even with the face of the mould-carriage, when the pusher-block comes forward and pushes the bricks off. It will be understood that the mould-carriage is at rest whilst the moulds are being filled, and whilst the clay in the moulds is being pressed, the draw-pawl *h*, at such times, advancing to seize another tooth, to draw the mould-carriage forward, and that, just as the mould-carriage begins to revolve, the pusher-block advances quickly and pushes off the bricks, and recedes in time to be in position for the next operation.

What I claim as my invention, and desire to secure by Letters Patent, is—

1. The combination and arrangement of the toggle-bars *e e'* and *f f'*, pitman *j*, crank and plunger *k*, with the mould-carriage *H*, operating substantially as and for the purposes herein specified.

2. The head-block *N*, provided with slots *q*, in combination with the plate *P*, provided with perforations *r r*, substantially as and for the purposes herein specified.

3. The combination of the pusher-block *O*, lever *V*, pin *x*, cam *R*, shaft *D*, and mould-carriage *H*, arranged and operating substantially as and for the purpose herein specified.

4. The arm *L'*, in combination with the mould-carriage *H* and plungers *J*, substantially as and for the purposes herein specified.

EDWARD FARON.
